CLAIM

The ornamental design for a boat, as shown and described.

DESCRIPTION

FIG. 1 is a front perspective view of a boat showing my design;

FIG. 2 is a left-hand side elevational view, wherein the right-hand side elevational view is substantially identical;

FIG. 3 is a top plan view;

FIG. 4 is a bottom plan view;

FIG. 5 is a front elevational view; and

FIG. 6 is a rear elevational view thereof.
